UNITED STATES PATENT OFFICE.

GEORGE L. LOBSITZ, OF NEWARK, NEW JERSEY, ASSIGNOR TO THE RANNEY
REFRIGERATOR COMPANY, OF GREENVILLE, MICHIGAN.

DESIGN FOR A HINGE.

SPECIFICATION forming part of Design No. 28,098, dated December 28, 1897.

Application filed October 22, 1897. Serial No. 656,101. Term of patent 14 years.

To all whom it may concern:

Be it known that I, GEORGE L. LOBSITZ, a citizen of the United States, residing at Newark, in the county of Essex and State of New Jersey, have invented a new and original Design for a Hinge, of which the following is a specification.

This invention relates to a new and original design for a hinge; and it has for its object to provide a design of this character that shall be both useful and ornamental.

The leading feature of the design resides in one leaf or member of the hinge being elongated and of a tapering width and provided with a triangular group of circular openings, scroll-webs extending between and around said openings, a leaf-like figure at one edge between two of the openings, and a triangular cluster of leaf-like figures at the outer extremity or point thereof, and the other hinge leaf or member being of a substantially triangular shape, with irregularly-scalloped edges, and provided with superficial lines or ridges scrolled toward the corner-angles of the leaf or member, the edge of said leaf or member at the apex thereof having a leaf-like configuration.

In the drawings, Figure 1 is a plan view of a hinge embodying the herein-described design. Fig. 2 is a longitudinal sectional view thereof.

Referring to the accompanying drawings, the numeral 1^a designates a hinge essentially comprising the separate leaves or members 1 and 2, respectively. The leaf or member 1 is elongated and of a tapering width and is provided with a triangular group of circular openings 3. The said leaf or member 1 is

further provided with scroll-webs 4, extending between and around said openings 3, a leaf-like figure 5 at one edge and between two of the openings 3, and a triangular cluster 6 of leaf-like figures located at the outer extremity or point thereof. The other hinge leaf or member 2 is of a substantial triangular shape, with an irregularly-scalloped edge, and is provided with superficial lines or ridges 7, scrolled toward the corner-angles of the leaf or member. The edge of the leaf or member 2 at the apex thereof has a leaf-like configuration, as indicated at 8, and which completes the essential features of the design.

The leaves or members 1 and 2 are provided at their adjacent corners with overlapping ears 9, connected together by the pintle 10, on which is arranged a spring 11, having separate reversely-coiled portions, a central approximately U-shaped loop 12, bearing against one of the leaves or members, and angled terminals 13, bearing against the other leaf or member, and, while the spring referred to forms a necessary part of the hinge, still it will be understood that the same forms no part of the design contemplated by the present invention.

What I claim is—

The design for a hinge, herein shown and described.

In testimony that I claim the foregoing as my own I have hereto affixed my signature in the presence of two witnesses.

GEO. L. LOBSITZ.
